UNITED STATES PATENT OFFICE.

MARK A. REPLOGLE, OF AKRON, OHIO, ASSIGNOR TO THE GOODYEAR TIRE & RUBBER COMPANY, OF AKRON, OHIO, A CORPORATION OF OHIO.

CEMENTING DEVICE.

1,316,805.

Specification of Letters Patent. Patented Sept. 23, 1919.

Application filed June 11, 1919. Serial No. 303,402.

To all whom it may concern:

Be it known that I, MARK A. REPLOGLE, a citizen of the United States, and resident of Akron, Ohio, have invented new and useful Improvements in Cementing Devices, of which the following is a specification.

My invention relates to a device for applying cement or other liquid to the edge of a moving sheet or strip of material.

10 More particularly my invention relates to a device for applying cement to the skived edge of a strip of rubber material in the course of the manufacture of rubber tubing, especially that used as inner tubes for tires.

15 It has been found, with devices hitherto in use for the purpose of cementing the edge of a traveling sheet of material, that the extreme outer edge would frequently not be treated with the cementing liquid owing 20 to its meandering motion, its unevenness or to its tendency to curl, and furthermore, it sometimes happened that so much liquid was applied that it would get on the side of the material which it was not desired to cement.

25 It is, accordingly, an object of my invention to provide a device wherein the several objections above referred to will be overcome or avoided.

30 A further object of my invention has been to provide a simple device that will uniformly apply a film of liquid to the edge of a moving strip of material without allowing the liquid to get on the wrong side of 35 the material and one which will compensate for any unevenness of travel of the material, or any curl at the edge thereof.

35 In the drawings, wherein I have illustrated the preferred embodiment of my invention and in which similar reference numerals designate like parts:

Figure 1 is a perspective view showing the device of my invention in operation;

Fig. 2 is an elevation; and

45 Fig. 3 is a detail of the cement applying element.

In the specific and particular embodiment of my invention herein disclosed an upright 10 is bolted or otherwise secured to any suitable support, and is provided at its upper 50 end with ears or lugs 11 between which is mounted a horizontally disposed pinion or gear 12 having a thumb nut 13 secured thereto by which the pinion may be rotated.

55 A rack 14 having its toothed surface 15

in mesh with the pinion 12, is fitted to slide between the pinion and a face of the upright, and be guided thereby.

From the outer end 16 of the rack, a swinging arm 17 is suspended so as to oscillate in a single plane. The arm 17 is bent near its lower end to form a shorter arm 18 which, when the device is in its operative position, is substantially horizontal. This shorter arm 18 serves as a bearing for a revoluble wheel, roll or other suitable element 19 the work-face of which is preferably concaved as shown in Figs. 2 and 3.

More specifically the preferred conformation of the work-face of the roll is that shown in Fig. 3, that is to say, in cross-section the line is straight for a portion of its length, A—B, it then takes an angle of approximately 15 degrees from the point B to the point C, for a length substantially equal to the width of the skived portion of the strip; from the point C the line rises on a curve of gradually increasing pitch to D, for a purpose that will presently appear.

Arranged below the roll, or wheel so as to surround the lower part thereof is a receptacle 21 in which the cement or other liquid is contained; the wheel dipping in the liquid as it is revolved by frictional contact with the material.

A strip or sheet of material 20 to the edge 20^a of which the liquid in the receptacle 21 is to be applied (specifically a strip of rubber material having a skived edge 20^b), is caused to travel so that the edge of the material is passed in proximity to the upright 10 and the element carried thereby. Any desired means such as a belt conveyer 22 may be utilized to cause the strip to move along continuously, uniformly and at a proper speed, suitable supports 23 being provided to keep the belt and strip from sagging. The belt should, of course, be narrower than the fabric, in order that the edges of the latter may project, and thus be engaged by the cementing element.

The operation of my device is as follows:

The strip of material 20 is brought in place on the conveyer belt 22 and the rack 14 is adjusted by means of the pinion 12 so that the point of support 16 of the arm 17 sufficiently overhangs the material, to cause the roll 19 to bear by gravity against the edge of the material. In other words the roll is suspended off center by the rack.

14. The contact of the moving strip 20 with the wheel 19 will, in operation, cause the wheel to revolve and apply to the edge 21 of the material a film of the liquid contained in the receptacle in which the wheel dips. Normally the skived portion 21^a of the strip is engaged by the part of the wheel B—C, as shown in Fig. 3, but, if the edge of the material should be curved at places, the 10 curved portion would nevertheless be cemented by reason of the curvature of the wheel face, and by the wheel's being pressed against the edge by gravity. In the same way if there be any unevenness of either in 15 the strip itself, or in its travel, the face of the wheel will closely follow the edge of the material.

While I have shown my device applied to but one edge of the strip 20 it is usually 20 customary to provide a similar device for the opposite edge, and by reversing the direction of travel of the strip, as by passing it over a friction roll or the like, to cement the other side of the material at its opposite 25 edge.

Although I have shown a specific embodiment of my invention and referred to its use in a particular industry, it will be understood that changes and modifications 30 may be made in the device without in any sense departing from the essence of the invention as defined by the appended claims, and that the device will have utility in many analogous arts.

35 What I claim is:

1. In a device of the character described, an element adapted to contact with the edge of a moving strip of material, means for applying a liquid to said element and means 40 for swingably suspending said element.

2. In a device of the character described, an element adapted to contact with the edge of a moving strip of material, means for applying a liquid to said element and adjustable means for swingably suspending said 45 element.

3. In a device of the character described, a revolute element adapted to contact with the edge of a moving sheet of material, means for maintaining contact between said 50 element and said strip comprising an oscillating support for said element, and means for applying a liquid to said element.

4. In a device of the character described, 55 a revolute element adapted to contact with the edge of a moving sheet of material, means for maintaining contact between said element and said strip comprising an oscillating support carrying said element and suspended from a point above said element, and means for applying a liquid to said element.

5. In a device of the character described, 60 a revolute element adapted to contact with the meandering edge of a moving sheet of

material and be revolved thereby, means for holding said element constantly in contact with said edge by gravity comprising a support for said element pivoted off center, and means for applying a liquid to said element. 70

6. In a device of the character described, a revolute element adapted to contact with the meandering edge of a moving strip of material, means for holding said element in 75 contact with said edge by gravity comprising an arm, a support for said arm, a swinging arm pivotally suspended from said first arm and carrying said element and means for applying a liquid to said element. 80

7. In a device of the character described, a revolute element adapted to contact with the meandering edge of a moving strip of material, means for holding said element in contact with said edge by gravity comprising an adjustable arm, a support for said arm, a swinging arm pivotally suspended from said first arm and carrying said element and means for applying a liquid to 85 said element. 90

8. In a device of the character described, a revolute element adapted to contact with the meandering edge of a moving strip of material, means for holding said element in contact with said edge by gravity comprising an arm, a support for said arm, a swinging arm pivotally suspended from said first arm and carrying said element and a liquid holding receptacle in which said element dips to apply liquid thereto. 95

9. In a device of the character described, means for applying liquid to the meandering edge of a moving strip of material, comprising a revolute element, means for suspending said element off center and means 105 for applying a liquid to said element. 100

10. In a device of the character described, means for applying liquid to the meandering edge of a moving strip of material, comprising a revolute element having a concave face adapted to contact with said edge, means for suspending said element so that it will press by gravity against said edge, and means for applying a liquid 110 to said element. 115

11. In a device of the character described, means for applying liquid to the meandering edge of a moving strip of material, comprising a revolute element, an arm suspended off center on which said element is carried, 120 and means for applying a liquid to said element.

12. In a device of the character described, means for applying liquid to the meandering edge of a moving strip of material, comprising a revolute element, an adjustable support, an arm suspended off center from said support and on which said element is carried, and means for applying a liquid to 125 said element. 130

13. In a device of the character described, means for applying liquid to the meandering edge of a moving strip of material, comprising a revoluble element having a curved surface, means for holding said curved surface of said element by gravity against said edge and means for applying a liquid to the curved surface of said element.

14. A device for applying cement to the skived edge of a moving strip of material, comprising in combination, a roll having a flared surface, means for suspending said roll off center whereby it bears by gravity against said edge, and means for applying cement to said flared surface.

15. A device for applying cement to the skived edge of a moving strip of material, comprising in combination, a roll cylindrical at one end, and flared at the other, so as to produce a concave outer surface, means for suspending said roll off center whereby it bears by gravity against said edge and means for applying cement to said surface.

16. A device for applying cement to the skived edge of a moving strip of material, comprising in combination, a roll having a flared surface, means for suspending said roll off center whereby it bears by gravity against said edge, a cement containing receptacle in which said roll dips to apply cement to said surface.

17. A device for applying cement to the skived edge of a moving strip of material,

comprising in combination, a roll having a flared surface, adjustable means for suspending said roll off center whereby it bears by gravity against said edge, and means for applying cement to said flared surface.

18. In an apparatus of the character described, means for causing a strip of material to travel longitudinally, a roll adapted to contact with said strip at the edge thereof, means above said roll from which said roll is suspended off center whereby said roll bears by gravity against said edge, and means for applying a liquid to said roll.

19. In an apparatus of the character described, means for causing a strip of material to travel longitudinally, a roll having a curved surface, a liquid-containing receptacle below said roll and in which said roll dips, an upright, a rack and pinion mounted on said upright, means for rotating said pinion to adjust said rack, an arm pivotally suspended from said rack, and supporting said roll, whereby said roll is pressed against the edge of said strip by gravity upon suitable adjustment of said rack.

In witness whereof, I have hereunto signed my name in the presence of two subscribing witnesses.

MARK A. REPOGLE.
